UNITED STATES PATENT OFFICE.

ERIC BLUCKER, OF CHICAGO, ILLINOIS.

TURBINE.

No. 829,942.

Specification of Letters Patent.

Patented Sept. 4, 1906.

Application filed January 11, 1905. Serial No. 240,634.

To all whom it may concern:

Be it known that I, ERIC BLUCKER, a citizen of the United States of America, and a resident of Chicago, Cook county, Illinois, have invented a certain new and useful Improvement in Turbines, of which the following is a specification.

My invention relates to turbines in general, and more particularly to turbines adapted to be driven by gas under pressure, and especially to turbines adapted to be driven by steam-pressure.

Generally stated, the object of my invention is to provide an improved, simplified, and highly efficient turbine adapted to be driven by any suitable fluid-pressure, but especially adapted to be driven by compressed air, steam, or other gas under pressure.

A special object is to provide an improved construction and arrangement by which a turbine when operated may advantageously and efficiently utilize the pressure of the steam or other gas and may utilize more or less of the expansive force of the steam or other gas, in addition to the usual utilization in motors of this character of the impact or velocity of the steam as it escapes from the jet-opening and impinges upon the surface of the movable part of the motor.

Another object is to provide an improved construction and arrangement whereby the turbine may exhaust freely through the hub portion of the rotary member, the tendency of the steam or other gas being with my improved construction to flow toward the axis or shaft of the rotary member.

A further object is to provide an improved construction or arrangement for reversing the turbine.

It is also an object to provide certain details and features of construction tending to increase the general efficiency and serviceability of a turbine of this particular character.

To the foregoing and other useful ends my invention consists in matters hereinafter set forth and claimed.

In the accompanying drawings, Figure 1 is a cross-section of a turbine involving the principles of my invention. Fig. 2 is a section on line 2 2 in Fig. 1. Fig. 3 is a view of the rotary member, showing certain portions in sections and certain other portions in side elevation. Fig. 4 is an inside view of one of the exhaust-chambers. Fig. 5 is an outside

view, partially in section, of one of said exhaust-chambers. Figs. 6 and 7 are perspectives of the two halves or sections of the rotary member. Fig. 8 is a detailed external view of the central portion of the rotary member. Fig. 9 is a diagram illustrating the flow of steam or other gas under pressure through the interior of the rotary member.

As thus illustrated, my improved turbine comprises a cylinder or casing A, supported in any suitable manner and provided on opposite sides with the shaft-bearings a and the exhaust-chambers a'. It will be seen that the exhaust-pipes a² communicate with said exhaust-chambers. The rotary member B is keyed to a shaft b. This shaft, it will be seen, rotates in the said bearings a. As shown, the said rotary member comprises two halves or sections b' b². These two halves or sections are ranged side by side upon the said shaft and are secured together by means of bolts b³. It will be observed that the hub portion of section b² is provided with a boss b⁴, adapted to fit into a recess b⁵, with which the hub of the other section is provided. Also it will be observed that section b' comprises an outer disk or side wall b⁶, provided at its outer edge with an annular band or flange b⁷. In a similar way the section b² comprises an outer flat wall b⁸, provided at its edge with an annular band or flange b⁹. When the two sections are assembled together, an annular slot b¹⁰ is left between the edges of the flanges b⁷ and b⁹. At their central portions each of said disks is provided with exhaust-openings l, arranged, preferably, in a circle concentric with the shaft. In addition the section b' is provided interiorly with obliquely-arranged blades b¹¹. The section b² is provided with similar blades b¹². In each case it will be seen that the said blades are arranged tangentially relatively to the two parts or sections of the hub b¹³ of the rotary member. (See Fig. 1.) It will be seen that the faces of the said blades are concave, while their backs are convex, and it will also be seen that the faces of all of the blades of the section b' extend obliquely across the circular path of travel, while the faces of all of the blades of the section b² are similarly mounted and arranged on an opposite angle. In this way it will be seen that the blades of the two sections—that is to say, the two sets of blades—have forwardly-converging faces.

110

Preferably each blade extends forwardly and obliquely across the circular path of travel, so as to extend beyond the edge of a blade on the other section and nearly to the face of the blade just in advance of said last-mentioned blade. With this arrangement the blades of one section interlock, so to speak, with the blades of the other section, thereby providing relatively narrow passages between the edges of the blades on one section and the faces of the blades on the other section, and vice versa. It will be seen that each passage 2 is so positioned that the steam or other gas may escape therefrom in jet form and impinge directly upon the face of the blade immediately preceding the one which is allotted to the same section and which, together with the opposing face of the blade of the other section, forms the said opening. Thus, when the steam enters the main inlet-port C, it first impinges at about the point where two blades of opposite sections converge, and then passes through the opening 2 at the apex or point at which the faces of the two blades converge. Then it passes in an oblique direction to the next space or compartment and impinges upon the blade immediately in advance of the one around the edge of which it has just passed. From this point it then escapes through the next opening or space 2, but in an opposite direction, and then impinges directly upon the face of the blade immediately preceding the one between the face of which and the edge of the other one it first passed after entering the interior of the engine-casing. It is evident, therefore, that the steam or other gas under pressure after entering the engine-casing through the port or jet opening C and after impinging upon the faces of the blades immediately obstructing said port-opening then shoots forward and passes the blades initially receiving the force of the steam-jet. Having done this, the steam or other gas under pressure passes on for some distance, back and forth or in zigzag fashion, as shown in Fig. 10, it being understood, of course, that this is possible by reason of the high velocity of the steam or other gas under pressure. In other words, the steam or other gas when it enters the engine-casing is traveling at such a high velocity that it not only impinges with considerable force upon the blades nearest at hand, but also and notwithstanding the high speed of the turbine then passes these blades and also passes several others in advance of the blade initially receiving the force of the jet. In this way the steam or other gas under pressure is given considerable opportunity to expand after striking the blade initially receiving the force of the jet, and thus acts successively upon several of the blades, the progressive action of the steam in this way being in the same direction that the blades are traveling.

In order to reverse the turbine, the valve D, controlling the flow of steam or other gas to the port or opening C, is closed and the valve E then opened. The valve E controls the passage of steam or other gas to the reversing-port F, through which the entering steam or other gas may act upon the backs of the blades. Whether the turbine is running ahead or backward, the steam flows or gravitates, so to speak, toward the center or axis of rotation and finally through the openings 1 into the exhaust-chambers a' at each side of the casing. While the steam is acting upon the blades it will be seen that the said exhaust-openings are covered for one-half of the rotation of the rotary member of the turbine by means of the arc-shaped portions G. These portions are rigid with the engine-casing and bear against the outer surfaces of the disks b⁶ b⁸. Consequently as soon as each exhaust-opening reaches the end of the adjacent arc-shaped portion G the steam is then free to escape into the chamber a', it being understood that this is the character of construction at each side of the turbine. As a matter of construction the outer corners of the blades can be provided with notches H, adapted to engage the edges or perimeters of the flanges b⁷ and b⁹. In this way the two halves or sections of the rotary member of the turbine are adapted to fit together and revolve as a solid or unitary body.

With the foregoing construction it is obvious that my improved turbine is of simple yet highly efficient character, that the velocity or impact of the steam or other gas under pressure is utilized in the well-known manner by means of blades secured to a rotary shaft, and that in addition the expansive force of steam or other gas under pressure after it has acted upon the blades initially receiving the force of the jet is free to expand in such a manner as to contribute materially to the pressure upon the turbine-blades.

What I claim as my invention is—

1. A turbine comprising a rotary hub, oppositely-arranged end walls provided at their outer edges with flanges having their edges separated for the purpose of providing an annular slot, tangentially-arranged blades secured to said hub and arranged between said end walls, said blades being arranged in two sets, each set being associated with one of said end walls and extending outwardly therefrom to such an extent as to overlap the outer edges of the blades of the other set, whereby a zigzag passage is provided between the two sets of blades, said passage extending around the hub to which the blades are secured, and an opening adapted to deliver a jet of steam or other gas under pressure against the faces of said blades, said zigzag passage permitting the said steam or other gas under pressure to travel ahead of

the blade initially receiving the force of the jet and act upon one or more blades immediately in advance thereof.

2. A turbine provided with a hollow rotary member having internally-arranged blades, said hollow member being provided at each side, near its center, with circular rows of exhaust-openings, together with a casing inclosing said rotary member, said casing being provided with portions adapted to cover said exhaust-openings for a portion of their circular path of travel, and also with exhaust-chambers into which the steam or other gas is admitted as soon as each exhaust-opening is opened or uncovered.

3. A turbine provided with a hollow rotary member, said rotary member having internally-arranged blades, said blades being set both obliquely to the circular line of travel and tangentially to the central portion of said rotary member, and the said blades being also arranged in two sets, with the members of the two sets slanting or converging forward relatively to their circular path of travel, and means for delivering a jet of steam or other gas under pressure against the faces of said blades.

4. A turbine comprising a rotary hub, oppositely-arranged end walls provided at their outer edges with flanges having their edges separated for the purpose of providing an annular slot, blades secured to said hub and arranged between said end walls, said blades being arranged in two sets, each set being

associated with one of said end walls and extending outwardly therefrom to such an extent as to overlap the outer edges of the blades of the other set, whereby a passage is provided between the sets of blades, and an opening adapted to deliver steam or gas under pressure to the ends of the blades.

5. A turbine provided with a hollow rotary member having internally-arranged blades, said hollow member being provided at each side with circular rows of exhaust-openings, an outer casing, said casing being provided with portions adapted to cover said exhaust-openings for a portion of their circular path of travel, and also with exhaust-chambers into which the steam or other gas is admitted as soon as each exhaust-opening is opened.

6. A turbine provided with a hollow rotary member, said rotary member having two sets of internally-arranged blades, said blades being set both obliquely to the circular line of travel and tangentially to the central portion of said rotary member, and means for delivering a jet of steam or other gas under pressure against the faces of said blades.

Signed by me at Chicago, Cook county, Illinois, this 30th day of November, 1904.

ERIC BLUCKER.
